CLAIM

We claim the ornamental design for a surgical instrument, as shown.

DESCRIPTION

FIG. 1 is a perspective view of a surgical instrument showing our new design;

FIG. 2 is a left side elevational view thereof;

FIG. 3 is a top plan view thereof;

FIG. 4 is a right side elevational view thereof;

FIG. 5 is a bottom plan view thereof;

FIG. 6 is a rear elevational view thereof; and,

FIG. 7 is a front elevational view thereof.

The broken lines show in FIGS. 1–7 are for illustrative purposes only and form no part of the claimed design.
